UNITED STATES PATENT OFFICE.

CHARLES J. BEST, OF OAKLAND, CALIFORNIA.

ORE-FURNACE.

979,921.

Specification of Letters Patent. Patented Dec. 27, 1910.

Application filed January 15, 1910. Serial No. 538,220.

To all whom it may concern:

Be it known that I, CHARLES J. BEST, a citizen of the United States, residing at Oakland, in the county of Alameda and 5 State of California, have invented a certain new and useful Improvement in Ore-Furnaces, of which the following is a specification.

My invention relates to roasting furnaces 10 and is illustrated in the accompanying drawings wherein—

Figure 1 is a sectional elevation; Fig. 2 a section along the line 2—2 of Fig. 1.

Like parts are indicated by like characters 15 in all the drawings.

The furnace A provided with fire boxes A¹, grates A², fire doors A³, ash pit A⁴, ash pit doors A⁵, has the centrally located flue B which is provided at its bottom with the receiving chamber B¹ and a clean out door B². The openings C arranged helically and ascending about the wall of the flue B are closed by the doors C² having in connection 20 shelves C³ extending from the wall of the flue approximately half way across it. The 25 staircase D ascending helically about the outside of the flue allows access to the holes C. The platform D¹ about the top of the flue is reached by the staircase D. The 30 openings E in the top E¹ of the flue having the covers E² may be used to feed the furnace. The pipe F leads from the top of the flue to the condensing chamber F¹, which 35 chamber is surrounded by water jacket F² having the cold water inlet F³ and hot water outlet F⁴. The pipe G provides an outlet from the condensing chamber for the gases.

The use and operation of my invention 40 are as follows: When fire is started in the fire boxes, the hot gases pass up through the flue and out through the condensing chamber to the atmosphere. Ore is fed in through the openings in the top of the flue and falls upon the shelves about the wall. These shelves 45 are helically arranged in such manner that ore falling from any one shelf falls upon a lower shelf and cannot by any possibility fall clear to the bottom of the flue. During the process of roasting, the ore is scraped 50 from the successive shelves by means of implements in the wall and falls to a lower shelf. This process is continued until the ore finally is discharged in the receiving chamber in the bottom of the flue from

which the roasted ore may be withdrawn. 55 The hot gases which pass into the condensing chamber are condensed and the cool gases allowed to pass off into the atmosphere.

I claim:

1. An ore roasting furnace comprising a 60 vertical flue, a combustion chamber connected so as to discharge thereinto at the bottom, and a series of horizontal overhanging helically arranged separated shelves on the inside of the flue. 65

2. An ore roasting furnace comprising a vertical flue, a combustion chamber connected so as to discharge thereinto at the bottom, and a series of overhanging helically arranged separated shelves of refractory material on the inside of the flue. 70

3. An ore roasting furnace comprising a vertical flue, a combustion chamber connected so as to discharge thereinto at the bottom, a series of overhanging separated 75 shelves on the inside of the flue, and an opening associated with each shelf whereby access can be had to it from the outside of the flue.

4. An ore roasting furnace comprising a 80 vertical flue, a combustion chamber connected so as to discharge thereinto at the bottom, a series of overhanging helically arranged separated shelves on the inside of the flue, and an opening associated with each 85 shelf whereby access can be had to it from the outside of the flue.

5. An ore roasting furnace comprising a vertical flue, a combustion chamber connected so as to discharge thereinto at the bottom, a series of overhanging separated 90 shelves of refractory material on the inside of the flue, and an opening associated with each shelf whereby access can be had to it from the outside of the flue. 95

6. An ore roasting furnace comprising a vertical flue, a combustion chamber connected so as to discharge thereinto at the bottom, a series of overhanging helically arranged separated shelves of refractory 100 material on the inside of the flue, and an opening associated with each shelf whereby access can be had to it from the outside of the flue.

7. An ore roasting furnace comprising a 105 vertical flue, a combustion chamber connected so as to discharge thereinto at the bottom, a series of overhanging separated

shelves on the inside of the flue, an opening associated with each shelf whereby access can be had to it from the outside of the flue, and a platform associated with each such opening on the exterior of the flue.

8. An ore roasting furnace comprising a vertical flue, a combustion chamber connected so as to discharge thereinto at the bottom, a series of overhanging helically 10 arranged separated shelves on the inside of the flue, an opening associated with each shelf whereby access can be had to it from the outside of the flue, and a platform associated with each such opening on the exterior 15 of the flue.

9. An ore roasting furnace comprising a vertical flue, a combustion chamber connected so as to discharge thereinto at the bottom, a series of overhanging separated 20 shelves of refractory material on the inside of the flue, an opening associated with each shelf whereby access can be had to it from the outside of the flue, and a platform associated with each such opening on the exterior 25 of the flue.

10. An ore roasting furnace comprising a vertical flue, a combustion chamber connected so as to discharge thereinto at the bottom, a series of overhanging helically 30 arranged separated shelves of refractory material on the inside of the flue, an opening associated with each shelf whereby access can be had to it from the outside of the flue,

and a platform associated with each such opening on the exterior of the flue.

35

11. An ore roasting furnace comprising a vertical flue, a combustion chamber connected so as to discharge thereinto at the bottom, a series of overhanging separated shelves on the inside of the flue, a door 40 through the flue associated with each such shelf, and a spiral stairway about the flue on the exterior thereof to give access to such doors.

12. An ore roasting furnace comprising a vertical flue, a combustion chamber connected so as to discharge thereinto at the bottom, a series of overhanging separated shelves on the inside of the flue, a door 45 through the flue associated with each such shelf, a helical stairway about the flue on the exterior thereof to give access to such doors, a fluid pipe leading from the top of the flue, and a condenser into which it discharges.

13. An ore roasting furnace comprising a vertical flue, a combustion chamber connected so as to discharge thereinto at the bottom and a series of overhanging separated shelves on the inside of the flue, said shelves helically arranged thereabout so as 50 to leave no continuous vertical opening 60 through the entire length of the flue.
